[57] CLAIM

The ornamental design for a wheel, as shown and described.

DESCRIPTION

FIG. 1 is a front-perspective view of a wheel showing my new design;

FIG. 2 is a front elevational view thereof, with the center cap omitted for clarity of illustration only;

FIG. 3 is a rear elevational view thereof;

FIG. 4 is a front elevational view of a second embodiment, wherein the only difference resides in the center mounting feature; and,

FIG. 5 is a cross-sectional view taken along line V—V of FIG. 4.
